CLAIM

The ornamental design for a camera lens, as shown and described.

DESCRIPTION

FIG. 1 is a front, left, bottom perspective view of a camera lens, showing our new design.

FIG. 2 is a perspective view taken from a rear, right, top plan side thereof,

FIG. 3 is a front elevation view thereof,

FIG. 4 is a rear elevation thereof,

FIG. 5 is a left side elevation view thereof,

FIG. 6 is a right side elevation view thereof,

FIG. 7 is a top plan view thereof,

FIG. 8 is a bottom plan view thereof,

FIG. 9 is another left side elevation view thereof; and,

FIG. 10 is a cross section thereof taken along a line 10-10 of FIG. 9, in which the inside mechanism of the camera lens, which is not claimed, is omitted.

The oblique line shading in FIGS. 5 and 6 indicates transparency.
